UNITED STATES PATENT OFFICE.

CHARLES SILGER AND ISAAC DEATHERAGE, OF DULUTH MINNESOTA.

CIGAR-BANDING DEVICE.

No. 898,273.

Specification of Letters Patent.

Patented Sept. 8, 1908.

Application filed January 18, 1908. Serial No. 411,427.

To all whom it may concern:

Be it known that we, CHARLES SILGER and ISAAC DEATHERAGE, citizens of the United States of America, residing at Duluth, in the county of St. Louis and State of Minnesota, have invented certain new and useful Improvements in Cigar-Banding Devices, of which the following is such a full, clear, and exact description as will enable others skilled 10 in the art to which it appertains to make and use the same.

Our invention seeks to provide a simple apparatus whereby the placing of bands around cigars will be facilitated and by 15 which the operator will be enabled to place the bands at any desired point of the cigar with certainty. These objects are attained by the use of the device illustrated in the accompanying drawings and the invention consists in certain novel features of the same as 20 will be hereinafter first fully described and then particularly pointed out in the claims.

In the drawings referred to, which show the preferred embodiment of the invention, 25 Figure 1 is a plan view of the device. Fig. 2 is an end view of the same. Fig. 3 is a longitudinal section taken on the line $x-x$ of Fig. 1, and Fig. 4 is a detail section on the line $y-y$ of Fig. 1.

30 In carrying out our invention, we employ a small table or block, 1, which is to be placed on the bench in front of the workman and which may be provided with legs, 2, as shown. A longitudinal slot, 3, of a shape 35 and size approximating the shape and size of the bands is formed through the body of this block or table and at one end of this slot is provided a reduced or narrower extension, 4, in the side walls of which are narrow vertical

40 slits or notches, 5. A follower, 6, is fitted in the slot 3 and is provided at one end with a somewhat elongated tongue, 7, which engages and plays in the extension 4 of the slot and is provided with narrow slits or notches, 45 8, in its sides registering with the slits 5 in the walls of the slot. This follower corresponds in shape to the slot and is fitted to slide freely therein in a vertical plane and is supported by a spring, 9, secured to the under

50 side of the table or block and exerting an upward pressure upon the follower. At one end of the block or table is a band-retainer or keeper, 10, which is arranged to project over the end of the extension 4 of the slot 3 and thereby rest upon the bands placed upon and carried by the follower. This keeper or re-

taining block is held in its position, in the form illustrated, by means of set screws, 11, inserted into the table through slots or notches, 12, in the ends of the keeper. At 60 about its center, the keeper is formed or provided with a well or reservoir, 13, which extends to an opening, 14, in the bottom of the keeper directly over the end of the follower so that paste or adhesive substance in the 65 well may flow to the ends of the labels or bands, as will be readily understood. As shown, the well 13 projects upward and rearward and is provided with a cover, 15, in which is mounted a worm or feed-screw, 16, 70 having a plunger-head, 17, at its lower end whereby the paste may be fed to the bands as required. As it sometimes may be more convenient to apply a small quantity of adhesive to the ends of labels or bands at the 75 time they are printed, we contemplate the provision of a wick, 18, which may be placed in the discharge opening 14 and extend across the well and slowly feed to the bands a slight amount of water from a supply 80 placed in the well. Between the keeper and the table are arranged a pair of guide plates, 19, which are clamped in place by the keeper when the set screws 11 are turned home. These guide plates are formed with depend- 85 ing fingers, 20, which enter the registering slits 5 and 8 so as to pass down and bear against the opposite edges of the bands and thereby aid in maintaining them in the proper position. If the keeper be slightly 90 loosened, the plates may be manually adjusted to the exact width of the bands so that bands of any width may be used in the device.

Disposed at right angles to the longitudinal slot 3 and approximately in the plane of the end of said slot, is a stop or rest, 21, consisting of a vertically disposed plate having a tongue 22 extending outward from its lower edge whereby it may be adjustably secured 95 upon the table, the securing means shown being a thumb screw, 23, inserted into the table through a longitudinal slot, 24, in the tongue.

The construction and arrangement of the 100 several parts of the device being thus made known, the manner of using the same will, it is thought, be readily understood. The bands or labels are placed on the follower and confined by the walls of the slot and the 105 guide plates with the keeper or reservoir projecting over the ends of the labels. The 110

transverse slide or tongue 22 is then adjusted to bring the stop plate or rest to such a point that a cigar placed on the table with its end against the rest will extend across the slot 5 and the bands therein so that the top band may be rolled over the cigar at the desired point. A cigar is indicated in position in dotted lines in Fig. 1. The desired adjustment of the parts having been effected, the 10 top band is rolled over the cigar and the cigar with the band held thereto is lifted from the table, the band being thereby drawn from under the keeper so that the moistened adhesive-containing end of the same may be 15 pressed against and secured to the main body thereof. As the band is withdrawn from under the keeper, the spring bearing against the under side of the follower forces the same upward so that the succeeding band is pressed 20 against the wick or the adhesive carried by the keeper, the device being thus automatically arranged for the application of a band to another cigar.

The device is very simple in its construction and manipulation and the application of bands to cigars is rendered certain by its use so that all bands applied to the cigars of one 25 lot may be rapidly applied to the same at a uniform distance from the ends thereof.

30 Having thus described our invention, what

we claim and desire to secure by Letters-Patent is:—

1. A cigar-banding apparatus comprising a cigar-supporting table provided with a slot 35 across which a cigar may extend, said slot having a reduced extension at one end, a band-supporting follower mounted in the slot and having a tongue engaging the reduced extension thereof, a keeper arranged above said tongue, and guide plates held by said keeper and extending into the extension of the slot.

2. A cigar-banding apparatus comprising a table upon which a cigar may be supported while a band is wrapped around it, the said 45 table having a slot to contain the bands and across which the cigar may extend transversely, a vertically-movable band-supporting follower mounted in said slot, a keeper mounted on the table and extending across 50 one end of the slot and a guide plate held by the keeper and extending into the slot.

In testimony whereof, we have signed this specification in the presence of two subscribing witnesses.

CHARLES SILGER.
ISAAC DEATHERAGE.
